UNITED STATES PATENT OFFICE.

ALBERT T. GAHAN, OF FRESNO, CALIFORNIA.

METHOD OF AND APPARATUS FOR CANNING FIGS.

Application filed July 7, 1926. Serial No. 120,969.

This invention relates to improvements in the fruit canning industry and particularly to the canning of figs. The figs are placed in syrup in their cans and then cooked somewhat before the cans are sealed. As is well known to those in the industry, however, the figs must be precooked before they are placed in the syrup in order to remove a peculiar flavor otherwise present. Up to the present time, 10 as far as I am aware, the figs have been precooked in bulk lots in large vats or the like from which the figs are then ladled out and placed in the cans for immersion in the syrup for further treatment. This handling 15 of the naturally delicate figs in their cooked and even more delicate and tender condition causes an appreciable percentage of the figs to split and be otherwise damaged and considerable loss is thereby entailed.

20 The principal object of my invention therefore is to eliminate the above objectionable features by arranging for the figs to be precooked after being placed in the cans and for passing the cans automatically and continuously from the precooking tank to the syrup tank, while providing for the positive draining of the water from the cans after they leave the precooking tank and before they enter the syrup tank.

30 By means of this arrangement any handling of the figs after they are once in a softened condition is avoided and the figs are never touched after they are once placed in the cans in their normal dry condition. Canning operations are therefore expedited and losses due to damaging of the figs by handling the same is eliminated.

40 A further object of the invention is to produce a simple and inexpensive device and yet one which will be exceedingly effective for the purpose for which it is designed.

These objects I accomplish by means of such structure and relative arrangement of parts as will fully appear by a perusal of 45 the following specification and claims.

In the drawings similar characters of reference indicate corresponding parts in the several views;

Fig. 1 is a sectional elevation of the precooking and syrup tanks showing the can container conveying apparatus arranged in connection therewith and with the containers in the positions occupied during their movement lengthwise of the tanks, to illustrate the method of positioning and handling the containers.

Fig. 2 is an enlarged cross section of the syrup tank and a can container therein taken on the line 2-2 of Fig. 1.

Fig. 3 is a vertical section of a can container.

Referring now more particularly to the characters of reference on the drawings, the numeral 1 denotes the water tank of any desired length beyond which and in alinement therewith is a separate tank 2 to contain syrup. The water in the tank 1 is maintained at a temperature suitable for precooking purposes in any desired manner, such as by means of a steam pipe 3 projecting lengthwise in the tank from the rear end thereof, the water being arranged to overflow from the front end of the tank. This permits the objectionable substance from the skin of the figs and rising to the 75 surface to overflow from the tank.

Disposed above the tanks adjacent the opposite ends of the same sprocket wheels 4 over which passes an endless chain 5. From the sprocket wheels the chain slopes downwardly at an angle and then extends horizontally and just above the respective tanks for the greater portion of the length thereof. Said chain is guided between the sprocket wheels wherever needed by idlers 6 and is supported for its full length between the sprocket wheels by a rigid channel or similar member 7, said member being arched upwardly at and between the adjacent ends of the tanks as at 8 so that the chain will 90 follow a similar path. The chain is driven so that its lower run travels from tank 1 toward the tank 2 by any suitable means, which it is not thought necessary to show.

The figs to be passed through the tanks are first placed in cans 9 which are temporarily packed in containers 10 which are formed as open topped rectangular boxes, the top of the cans being left open. The bottoms of the containers are permanently attached but are preferably of slatted or similar construction to allow the free flow of water therethrough. The contents of the cans are prevented from falling out when the boxes are turned on edge by removable screen frames 11 which are detachably mounted over the top of the boxes in any suitable manner.

The upper faces of the boxes (which denote those faces which project upwardly 110 when the boxes are tipped as above stated) have eyes 12 thereon to be engaged by for-

wardly facing hooks 13 projecting at intervals from the chain. The width of the boxes is such that they will pass free between the sides of the tank.

5 In operation the boxes are hung one by one onto the chain hooks at the forward end of the tank 1, so that the screen covers on the boxes face the forward end of the tank. With the longitudinal travel of the 10 chains the boxes are gradually lowered and immersed into the water in the tank 1, until they ride on longitudinal runners 14 mounted in the tank, the boxes being then completely immersed in the water. The runners 15 are so disposed as to take the weight of the boxes from the chains and the longitudinal movement of the latter then causes the boxes to be dragged along the runners and said boxes then assume a slight tilt toward the 20 rear, as shown in Fig. 1. When the boxes are in this position the water may freely flow into and out of the cans, precooking the contents, without the possibility of air pockets being formed in the cans on account of 25 the rearward tilt of the boxes and the consequent forward and upward tilt of the cans.

As the boxes reach the rear end of the tank and the chains start on their upward slope, the boxes are lifted from the runners 30 and are freely suspended from the hooks. When in this position the boxes assume a forward tilt, or one opposite to that had while in the tank. This is owing to the positioning of the eyes 12 which is forwardly 35 of the vertical center line of the boxes. The arch channel portion 8 of the chain supporting member is so arranged that with the continued movement of the chain the boxes will be raised clear of the rear end 40 of the tank 1, moved beyond the adjacent end of the tank 2 in clearance relation therewith, and then downwardly into said tank 2. The distance and length of time between 45 lifting the boxes out of the one tank and their immersion into the other is sufficient to insure all water draining out of the boxes and cans, which it will readily do on account of the downward slant of the cans then had.

As the boxes become immersed in the 50 syrup in the tank 2 they ride on runners 55 in said tank which causes the boxes to assume a tilt the same as that had in the tank 1 and for the same purpose. As the chain rises to the sprocket 4 at the rear end 60 of tank 2, the boxes will be suspended from the hooks, and will again assume a rearward tilt as before. This allows the syrup to drain from the cans. With the upward movement of the chains about said rear 65 sprockets the hooks 13 tend to disengage themselves from the eyes 12, the rear sprocket 4 being beyond the tank 2, a sufficient distance to enable the boxes to drop clear of the tank.

70 In connection with this apparatus, I con-

template using a mechanical conveying device to then receive and carry the boxes as released away from the syrup tank, the conveyor running at such a speed relative to that of the chain 5 as will cause the boxes to be suitably separated with the screen covers upwardly. The screens may then be removed from the boxes and the cans likewise removed for further treatment as usual.

It may here be noted that the syrup is being continuously changed in the tank 2, by adding syrup to the top of the tank and pumping the syrup from the bottom of tank 2 to a storage tank. In this tank the syrup is strained and tested for its sugar content 80 and is then used to refill the cans before the latter pass to the closing machine.

From the foregoing description it will be readily seen that I have produced such a device as substantially fulfills the objects 85 of the invention as set forth herein.

While this specification sets forth in detail the present and preferred construction of the device, still in practice such deviations from such detail may be resorted to as do not 90 form a departure from the spirit of the invention, as defined by the appended claims.

Having thus described my invention what I claim as new and useful and desire to secure by Letters Patent is:

95 1. In fig canning, a method of treating the figs consisting in placing the figs in open cans, immersing the cans in heated water to precook the figs, and then removing the cans from the water and immersing them in syrup.

2. In fig canning, a method of treating the figs consisting in placing the figs in open cans, immersing the cans in heated water to precook the figs, and then removing the cans 105 from the water and immersing them in syrup, all with a continuous operation.

3. In fig canning, a method of treating the figs consisting in placing the figs in open cans, immersing and moving the cans 110 through heated water to precook the figs, removing the cans from the water and at the same time causing the water to be drained from the cans, and then immersing the cans in syrup.

115 4. In fig canning, a method of treating the figs consisting in placing the figs in open cans, immersing the cans in heated water to precook the figs, causing the cans to be moved through the water, and then causing the cans to be automatically raised from the water and subsequently filled with syrup.

120 5. An apparatus for treating figs in open cans comprising separated water and syrup tanks, and means mounted in connection with the tanks for moving the cans into, along and then out of said water tank and into, along and out of the syrup tank with a continuous operation.

125 6. An apparatus for treating figs in open 130

cans comprising separated water and syrup tanks, means mounted in connection with the tanks for moving the cans into, along and then out of said water tank and into, along 5 and out of the syrup tank, and means whereby the water will be drained from the cans intermediate their movement from the one tank to the other.

7. An apparatus for treating figs in cans 10 comprising a water tank, means mounted in connection with the tank for moving the cans along the tank under water, and then raising the cans out of the water, means whereby with the movement of the cans under water said cans will be caused to assume an upward tilt toward their open ends, and means whereby as the cans are raised out of the water the tilt will be automatically reversed.

20 8. An apparatus for treating figs in open cans comprising separated water and syrup tanks, means mounted in connection with the tanks for moving the cans into, along and then out of said water tank and into, 25 along and out of the syrup tank, means causing the cans to assume a downward tilt toward their open ends as they are raised out of the water, and means causing the cans to assume a tilt in the opposite direction as 30 they are raised out of the syrup tank.

9. An apparatus for treating figs in open cans comprising separated water and syrup tanks, and means mounted in connection with the tanks for causing the cans to be 35 first immersed in the water tank and subsequently in the syrup tank with a continuous operation.

10. An apparatus for treating figs comprising separated open-topped water and 40 syrup tanks, an endless member mounted over the tanks and movable lengthwise thereof, a container to receive an open can in a substantially horizontal position, means for suspending the container from the endless 45 member, and means supporting and guiding said member in a manner to permit the container, with the longitudinal movement of said member, to be immersed in the water and moved along the water tank; then raised 50 clear of said tank; then lowered into and moved along the syrup tank, and finally raised from said syrup tank.

11. An apparatus for treating figs comprising separated open-topped water and 55 syrup tanks, said tanks being alined, vertically disposed sprocket wheels over said tanks adjacent the opposite ends thereof, a chain passing over said wheels, said chain sloping downwardly from the wheels, means 60 guiding and supporting the chain in a manner to maintain the same substantially horizontal for the major portion of the length of the tanks but causing said chain to arch upwardly adjacent the ends of and between 65 the tanks, hooks projecting outwardly from

the chain at intervals, containers to receive cans in a horizontal position, and an eye on each container to engage a hook; the chain supporting structure being so disposed relative to the tank as to enable the container to 70 be immersed in one tank and then removed from said tank and immersed in the other tank with the travel of the chain along the supporting means.

12. An apparatus for treating figs including an open-topped water tank, a movable chain disposed lengthwise of and above the tank, a sprocket wheel to which the chain slopes upwardly at the forward end of the tank, means at the other end of the tank for 80 causing the chain to slope upwardly from the tank, a hook projecting outwardly from the chain, a container to receive cans in a horizontal position, an eye on the container for engagement with the hook, means whereby when the container is suspended from the hook and lowered into the tank with the travel of the chain the container will automatically assume a slant such that the cans slope upwardly toward their mouth, and 90 means whereby as the hook moves upwardly with the chain at the opposite end of the tank the slant of the container and cans will be reversed.

13. An apparatus for treating figs including an open-topped water tank, a movable chain disposed lengthwise of and above the tank, a sprocket wheel to which the chain slopes upwardly at the forward end of the tank, means at the other end of the 100 tank for causing the chain to slope upwardly from the tank, a hook projecting outwardly from the chain, a container to receive cans in a horizontal position, an eye on the container for engagement with the hook, the 105 cans being open and facing the forward end of the tank; and the eye being disposed ahead of the vertical center line of the container, and runners in the tank to support the weight of the container when the latter 110 is lowered into the tank by the movement of the chain.

14. In fig canning, a method of initially treating the figs consisting in placing the figs in open cans, passing the cans through a pre-cooking medium, and then adding a preservative to the figs.

15. In fig canning, a method of initially treating the figs consisting in placing the figs in open cans, passing the cans through 120 heated water to precook the figs, draining the water from the cans, and adding syrup to the figs.

16. An apparatus for treating figs in open cans comprising a water tank and a syruping means beyond the tank, means mounted in connection with the tank and syruping means for moving the cans into, along and then out of said tank and then past the syruping means, and means for causing the 130

water to be drained from the cans as they leave the tank.

17. An apparatus for treating figs including an open-topped water tank, an endless member mounted over the tank and movable lengthwise thereof, a container to receive an open can, means for suspending the container from said member so that the can is substantially horizontal, and means

supporting and guiding said member in a manner to cause the container, with the longitudinal movement of said member, to be lowered into water at one end of the tank, moved through the water to the other end of the tank and then raised out of the water. 15

In testimony whereof I affix my signature.

ALBERT T. GAHAN.
